DOLL BUGGY SIDE PANEL

Burton W. Hazelton, Kirkwood, Mo. (9% Hazelton Products Inc., Box 206, Valley Park, Mo. 63088)

Filed Apr. 12, 1965, Ser. No. 84,723

Term of patent 14 years

(Cl. D34—15)

FIG. 1

FIG. 2

FIG. 3

FIG. 1 is a side elevation of the panel, showing the same as part of a buggy body, with buggy underframe, wheels and handle indicated in broken lines for illustrative purposes only.

FIG. 2 is a transverse vertical section on line 2—2 of FIG. 1, showing the offset in the panel near the longitudinal center thereof.

FIG. 3 is a transverse vertical section on line 3—3 of FIG. 1, showing the offset in the panel near one end thereof.

I claim:

The ornamental design for a doll buggy side panel, substantially as shown and described.
